UNITED STATES PATENT OFFICE.

CHARLEY THOMAS PATTERSON, OF SPRINGFIELD, MISSOURI.

FEED-MIXING DEVICE.

Application filed February 15, 1923. Serial No. 619,246.

To all whom it may concern:

Be it known that I, CHARLEY T. PATTERSON, a citizen of the United States, and a resident of Springfield, in the county of Greene and State of Missouri, have invented certain new and useful Improvements in Feed-Mixing Devices, of which the following is a specification.

My present invention relates generally to the making of stock and poultry foods, and more particularly to a mixing device which may be easily and quickly manipulated to thoroughly mix the grains and other feed, capable of being used in the home.

My object is the provision of a simple inexpensive device of this nature by which the desired result can be obtained in an effective efficient manner as well as conveniently and with minimum effort and trouble.

In the accompanying drawings which illustrate my present invention and form a part of this specification,

Figure 1 is a side elevation of my improved device,

Figure 2 is a vertical longitudinal section therethrough,

Figure 3 is a top plan view,

Figure 4 is a detail perspective view of one of the partition plates, and

Figure 5 is a side view partly in section, and upon a reduced scale, illustrating a slightly modified form.

Referring now to these figures my invention proposes a device including a vertically disposed mixing box 10 and a horizontally disposed feed box 11, both of said boxes forming parts of a rigid frame including front uprights 12 formed of any suitable material as, for instance, angle iron and intermediate uprights 13 which may also be formed of angle iron. In this frame the feed box 11 is supported in elevated position with its upper portion open to receive feed to be mixed, which is preferably introduced therein, in layers. At one end this feed box 11 opens into and communicates with the upper portion of the mixing box 10, the upper portions of the intermediate uprights 13 extending vertically at opposite sides of this mentioned end of the feed box so that these said upper portions of the intermediate uprights 13 form stops for partition plates 14 adapted to extend transversely of and slidably interfit the feed box 11 at various points between its discharge end in communication with the mixing box,

and its follower or feed plate 15 which also slidably interfits the same and is movable for the full length of the feed box toward its discharge end by virtue of flexible connections 16 secured at one end thereto and having their opposite ends connected to a winding drum 17. This drum is secured upon a shaft 18 mounted transversely through the mixing box 10 and provided at one outer end with a crank 19 by which it may be rotated, and with a ratchet wheel 20 with which a dog 21 is engagable to prevent movement of the follower or feed plate 15 in an outward direction within the feed box except when it is desired to do so preparatory to a refilling of the feed box. In order to permit of passage of the flexible connections 16, it will be noted that each of the partition plates 14, in addition to an upper slot 22 affording a hand hold, may have vertical side slots 23 through which the connections extend although it is apparent these slots may be dispensed with and the flexible connections extended along the side walls at the side edges of the partition plates. It is obvious that in the feed movement each partition plate when positioned at the discharge end of the feed box and when in engagement with the stops formed by the upper portions of the intermediate uprights 13, becomes a feed cut off which checks the movement of material from the feed box into the mixing box and thus the several feed plates measure the feed into separate charges for the mixing box and each plate in turn checks further feed into the mixing box until it is removed.

In the lower portion of the mixing box 10 is a mixed feed bin 24, which may be integral therewith or removable therefrom as shown, and which is in either instance provided at its outer side with an inclined scoop board 25 and is positioned beneath the semicylindrical base 26 of the mixing chamber within the latter of which a mixing wheel is mounted on a shaft 27 rotatable immediately above the chamber base 26. This base 26 of the mixing chamber has a discharge slot 28, at opposite sides of which are guides 29 adapted to slidably receive the side edges of a discharge plate 30, shiftable inwardly through one side wall of the mixing box 10 as indicated in Figure 1 and provided, as shown in this figure with a handle 31 by means of which it

may be readily inserted and withdrawn, in the latter instance permitting of the fall of mixed grain from the mixing chamber into the bin 24.

5 The mixing wheel is preferably formed of a pair of end plates 32 to which are rigidly secured the ends of a peripheral series of blades 33 preferably of the angular form shown, these blades forming mixing paddles, and the mixing wheel shaft 27 is journaled through the side walls of the mixing box 10 and provided at one end with a crank 27^a by means of which it may be readily and easily rotated.

15 Thus in operation the follower or feed plate 15 is shifted to the outer end of the feed box 11 in the position shown in Figure 2 and one at least of the partition plates 14 is inserted at the inner discharge end of the feed box against the stops formed by the upper ends of the intermediate partitions 13. Other partition plates 14 may be inserted at spaced points as seen in Figure 2 in order to divide the feed box, each checking the feed as it comes into engagement with the upper ends of the intermediate uprights.

The materials to be mixed are then introduced into the feed box and spread out in superposed layers between the feed plates 14 and between the rearmost feed plate and the follower 15, after which the first partition plate that is the one against the upper portions of the intermediate uprights is removed and the crank 19 rotated so as to draw the follower or feed plate 15 toward the inner discharge end of the feed box until the next feed plate 14 comes into engagement with the stops formed by the upper portions of the intermediate uprights. For further feed this plate must then be removed. At the same time the mixing wheel is rotated by means of its crank 27^a, in either a clockwise or counter-clockwise direction dependent upon the angularity of the blades so that as the material falls into the feed chamber through the open discharge end of the feed box, the material will be caught, and thoroughly intermixed before it falls to the base of the mixing chamber. Upon withdrawal of the discharge slide 30 the materials so mixed will fall into the bin 24, from which they may be withdrawn either by means of a scoop thrust inwardly upon the scoop board 25, or by first reinserting the feed slide 30 and bodily removing the bin 24 from the lower portion of the mixing box.

60 Instead of the partition plates 14 I may use a simple feed control gate between the feed box 11 and the mixing box 10, of any suitable construction, and which may take the form shown in Figure 5. In this figure a feed control gate is shown consisting of

a vertical series of spaced, parallel cross 65 plates 35 capable of preventing the fall of material under normal conditions, and at the same time providing for ready movement of material between the said cross plates when the follower is drawn forwardly.

It is obvious from the foregoing that the device proposed by my invention is simple and economical both as to first cost and upkeep and it is further obvious that it 75 will not only be capable of quick easy installation but is well adapted to efficiently perform the desired function.

I claim:

1. A feed mixer including an upright 80 mixing box having a mixing chamber and a mixing device within said chamber, a feed box in communication at one end with the upper portion of the mixing box, a frame of which the mixing and feed boxes form 85 parts, having uprights certain of which project at their upper portions along opposite sides of the discharge end of the feed box to form stops, a feed plate shiftable lengthwise of the feed box, and partition plates 90 insertable within the feed box and movable therein against the said stops.

2. A feed mixer including an upright mixing box having a mixing chamber and a mixing device within said chamber, a feed box in communication at one end with the upper portion of the mixing box, a frame of which the mixing and feed boxes form parts, having uprights certain of which project at their upper portions along opposite sides of the discharge end of the feed box to form stops, a feed plate disposed within and shiftable lengthwise of the feed box, flexible connections extending from said feed plate through the feed box and into the upper portion of the mixing box, a winding drum journaled in the upper portion of the feed box for said flexible connections, having a crank, and partition plates for disposition within the feed box, movable therein against said stops, and having vertical slots through which the flexible connections extend.

3. A feed mixer including an upright mixing box having a mixing chamber therein and a mixing device within the chamber, a feed box communicating at one end with the upper portion of the mixing box, having stops adjacent to the mixing box, a feed plate shiftable lengthwise of the feed box to shift material therefrom into the mixing box, and partition plates removably disposed within the feed box to separate the feed therein, each partition plate being movable with the feed toward and engageable with said stops adjacent to the mixing box, to cut off feed thereto.

CHARLEY THOMAS PATTERSON.
